UNITED STATES PATENT OFFICE.

OLIVER M. RHODES, OF CANTON, OHIO.

TOY.

1,110,823.

Specification of Letters Patent. Patented Sept. 15, 1914.

Application filed March 14, 1914. Serial No. 824,602.

To all whom it may concern:

Be it known that I, OLIVER M. RHODES, a citizen of the United States, residing at Canton, in the county of Stark and State 5 of Ohio, have invented certain new and useful Improvements in Toys.

My invention relates to that class of toys commonly known as mechanical toys and the objects of the present invention, are 10 first, to provide a simple structure, cheap in construction, and second, to provide means whereby the box or body carried by the traveling wheels may be moved or dumped into position to discharge the contents of 15 the box. These objects, together with other objects, readily apparent to those skilled in the art, I attain by the construction illustrated in the accompanying drawings, although my invention may be embodied in 20 a variety of other mechanical forms, the construction illustrated being chosen by way of example.

In the accompanying drawing: Figure 1 is a side view. Fig. 2 is a top view showing parts broken away. Fig. 3 is a side view showing a modified form. Fig. 4 is a view showing a portion of one of the shafts, and the dump lever and hook. Fig. 5 is a similar view showing a slight modification of the hook. Fig. 6 is a view showing a rear portion of the tongue, the axle and dump box connecting members.

Similar numerals of reference indicate corresponding parts in all the figures of 35 the drawing.

In the accompanying drawing, 1 represents the box or body, which is pivotally mounted intermediate its ends and at such a point that it will automatically assume 40 the position shown in dotted lines Figs. 1 and 3 when released. The axle 2 is properly journaled in suitable bearings such as 3 and 4, reference being had to the specific construction, which construction may be of 45 the form shown in Figs. 1 and 2, that is to say the relatively fixed bottom 5 may be provided, or the bearings may be formed as shown in Fig. 6, this being a question of judgment as the particular manner of journaling the axle has no specific reference to 50 the present invention.

Upon the axle 2 are mounted the traveling wheels 6, which are securely connected in any convenient and well known manner 55 to the axle 2 and are so connected that the

axle will be rotated by the rotation of the wheels 6. The shafts 7 or the tongue 8 extends forward and when it is desired to attach a body of an animal 9 such as a horse or dog, the tongue proper is formed substantially as shown in Figs. 1 and 2, by which arrangement the body 9 can be pivoted intermediate its ends and a rocking motion can be imparted as hereinafter described.

For the purpose of supporting the body in such a manner that the feet will not come in contact or drag upon the floor, the runner 10 is provided, which runner may be of the form shown or it may be of any other 60 desired form. For the purpose of imparting a rocking movement to the body 9 the axle 2 is provided with the crank 11, to which crank is journaled the rod 12, the opposite end of said rod being pivotally attached to one of the hind legs 13 of the body 9. In order that the proper rocking movement of the body 9 may be imparted by the crank 11 and the rod 12, the legs 75 of the animal are formed rigid so that there can be no pivotal or swinging movement, thereby producing a rigid connection between the rod 12 and the body 9 so that the body can rock upon the cross bar 14 held in the loops 14^a. The box 1 is normally held in the position shown in Figs. 1 and 3 by means of the cord 15, the holding lever 16 and the hook 17, said hook being so formed that it will engage one of the shafts 7 on the tongue 8 and hold the 80 lever 16 in an elevated position and when the lever 16 is held by the hook 17 the cord 15 will hold the box 1 in the position shown in Figs. 1 and 3; but when the lever 16 is released and permitted to drop into 85 the position shown in the dotted lines, Fig. 1, the cord 15 will be released and the box 1 permitted to be dumped into the position shown in dotted lines, Figs. 1 and 3 by reason of the fact that said box is held by 90 means of the cord 15 being connected to the loop 18 and to the front or forward end of the box 1, said cord passing through the aperture 19 in the relatively fixed bottom 5 or between the bifurcated members of the 95 tongue 8.

The lever 16 is pivotally connected to the bracket 20, which bracket is connected to one of the shafts 7 or the tongue 8 as the case may be, as it is simply a question of 100 110

judgment. It will be understood that a pull string 21 should be attached to the front ends of the shafts 7, so that the toy can be pulled over and upon a floor or carpet and when desired to tilt or dump the box 1 the lever 16 is simply detached and the box permitted to fall by gravity into the position shown in dotted lines Figs. 1 and 3, said box turning upon the pivotal points 22 or their equivalents.

When the relatively fixed bottom 5 is employed the seat 23 may be attached to said bottom, said seat being located substantially as shown, but it is a question of judgment 15 whether or not a seat is to be attached.

Having fully described my invention what I claim as new and desire to secure by Letters Patent, is:

1. In a toy of the class described, a pivoted box mounted upon a traveling frame, said box pivoted intermediate its ends, a tongue having pivotally connected thereto a rocking body, means for rocking said body by the movement of the toy, a lever provided at its outer end with a retaining hook, said retaining hook adapted for engagement with the tongue, and said lever pivotally connected at its opposite end to said tongue, a cord connected intermediate the ends of 25 the lever and to the forward end of the pivoted box, and means for supporting said tongue.

2. In a toy of the class described, the com-

bination of an axle provided with a crank and traveling wheels, a box located above 35 the axle and pivoted intermediate its ends, a tongue provided with a pivoted lever, means for holding the free end of the lever to the tongue and a cord connected to said lever and to the forward end of the pivoted 40 box, and means for supporting said tongue.

3. In a toy of the class described, the combination of a traveling frame provided with a tongue, a lever pivoted intermediate the 45 ends of the tongue, said lever provided with a hook adapted to engage the tongue, a box pivoted intermediate its ends and a cord connected to the lever intermediate its ends and to the forward end of the pivoted box, and means for supporting said tongue. 50

4. In a toy of the class described, the combination of a traveling frame provided with a tongue, a lever pivoted intermediate the ends of the tongue, said lever provided with a hook adapted to engage the tongue, a box 55 pivoted intermediate its ends and a cord connected to the lever and to the forward end of the pivoted box, and means for supporting said tongue.

In testimony that I claim the above, I 60 have hereunto subscribed my name in the presence of two witnesses.

OLIVER M. RHODES.
